STOKER

Clifford H. Snyder, Dormont, and Andrew W. Ferguson, Bellevue, Pa.; said Ferguson assignor to said Snyder

Application May 2, 1936, Serial No. 77,508

10 Claims. (Cl. 110—45)

This invention relates generally to solid fuel burning, and more particularly to a method and means for agitating said fuel as it is being burned.

This invention may be conveniently applied to 5 stokers arranged to burn solid fuel, and is particularly adaptable to underfed stokers.

In underfed stokers coal is fed from below by 10 means of a screw or other conveying or propelling device, and a forced draft is usually applied under or into the fire to support and accelerate forced combustion of the fuel. These two operations are usually served by a motor or motors energized by automatic electric controls. These controls operate the stoker in a cycle which may be 15 divided into two distinct periods, namely the firing period and the dormant period.

During the firing period as the fresh green 20 coal is fed upwardly through the retort from below it is preheated by the fire or hot coals thereabove. With coking coals and many so-called non-coking coals, as this preheating action takes 25 place the gases and natural oils are driven off and the coal particles become soft or semi-plastic, adhering one to the other, and ultimately forming a solid mass of coke. This solid mass is moved upward by the feeding of new green coal 30 from below and, instead of spreading out to form an even fuel bed as is desirable, it usually continues to build up, forming a hard shaft of coke, commonly known in the stoker industry as a 35 "coke tree".

The forced draft is unable to penetrate this coke tree so that blow holes usually exist around its base which results in a poor heat producing 40 fuel bed. Only after a lengthy firing period does this coke tree build up to a height great enough to fall over of its own weight, in which case the fire is sometimes lifted out of the retort, or the coke tree comes into contact with some obstruction 45 in its travel that will cause it to buckle and fall. However due to the large quantity of unburned fuel in the coke tree the fire often continues to give off an excessive amount of heat with a corresponding waste of fuel during the 50 dormant period, long after the demand for heat has been satisfied. In an effort to avoid these and the other coke tree disadvantages many stoker owners rake and poke the coke trees and level the fire by hand at frequent intervals.

The principal object of this invention is the 55 provision of agitating means for the preventing of the formation of solid masses of coke in the fuel before the fuel moves upwardly into the zone of combustion to maintain a homogeneous fuel bed.

Another object of this invention is the provision of means for agitating the coal by displacement, as it is being coked, so that the coked particles more readily correspond to the particles of coal from which they were formed. 5

Another object of this invention is the provision of means for agitating the coke by displacement, thereby loosening the coked fuel to maintain a loose fire bed that may be readily penetrated by a forced draft to promote better combustion, thereby producing more rapid conversion of the fuel into heat. 10

Other objects and advantages will appear hereinafter.

In the accompanying drawing wherein we show 15 a practical embodiment of the principles of this invention:

Fig. 1 is a vertical section taken through the feeding mechanism and retort of a typical automatic stoker, showing the application of this invention, parts being broken away. 20

Fig. 2 is a vertical section of a modified form 25 of the power transmission for operating the agitating device of this invention.

Fig. 3 is a vertical section of a retort showing 25 a modification of this invention applied thereto, with parts being broken away.

Fig. 4 is a side elevation looking to the right of the line 4—4 in Fig. 3.

Referring to Fig. 1 of the drawing, 10 represents the retort of an automatic underfed stoker arranged to be inserted or built into the fire box of a furnace or other related unit. This retort comprises the tuyère 11, upwardly expanding, provided with an interior chamber 12 opening 35 at the bottom 13 thereof for the conduction of air and provided with a plurality of inwardly directed passageways 14 ending in the ports 15 which open through the inner wall of the tuyère. Likewise the outer adjacent side wall of the 40 tuyère is provided with the passageways 16 for directing air from the chamber 12 along the floor line 17.

The tuyère 11 is mounted on the retort base 18 which comprises an inner casing 19. The inner 45 bore of the casing 19 forms the throat 20, the surface of which is continuous with the inner surface of the tuyère 11.

One side of the lower end of the casing 19 is provided with the passageway or conduit 21 for 50 admitting fuel to the bottom of the retort 10. A portion of the wall opposite the mouth of the conduit 21 deflects the fuel vertically upward through the throat to the burner or fire bowl formed by the tuyère 11. 55

The outer and lower part of the base 18 forms the wind box 22 which is connected to a source of air supply and serves to distribute the air evenly into the passageways 14 and 16 of the tuyère.

23 represents a screw for feeding solid fuel to the base of the retort, and which extends from the operating mechanism 24 through the base 25 of the fuel hopper 26, and through the screw housing 27 into the passageway 24 in the base 18 of the retort 10.

When the operating mechanism 24 is started, the screw 23 is rotated, thereby receiving coal from the hopper 26 and moving it through the housing 27 into the base 18 of the retort.

As coal is being fed to the retort it moves through the throat 20 into the fire zone in the bowl formed by the tuyère 11 and should spill, in a semi-burned condition, over the top thereof onto the floor 17. During this time the wind box 22 is delivering air to the passageways 14 and 16 of the tuyère 11 from whence it is forced into the burning fuel.

The coal in the lower part of the tuyère bowl 19 and in the throat 20 is being preheated and gassed and coke is formed. As the temperature increases in the preheating area or zone, the particles of coal change to a soft state due to the reaction of the natural oils therein, the coal particles having a tendency to adhere one to another and to form a solid mass of hard texture coke, as the gases and oils are driven off and the heat dries out the thus formed coke.

One object of this invention is to prevent this coke from forming into a solid mass by providing the retort 10 with the agitator bar 30 which in Fig. 1, is shown to be a section of a ring, the center of which is located at the point 31. The agitator is preferably circular in cross section and is supported at the lower end by the link 32 pivoted at 31 and riding in the bearing 33 of the casing 19, which bearing is formed to fit the perimetral contour of the agitator bar.

34 represents a transmission rod which is connected at one end to and which is arranged to be reciprocated by the crank 35 operated by the pinion 36 which in turn is driven by the beveled ring gear 37 affixed to the rotary shaft 28.

The other end of the transmission rod 34 is provided with a bifurcated member 38 which is pivotally secured in the bearing 39 near the outer end of the link 32.

Thus when the fuel screw 23 is operated, the shaft 28 will drive the crank arm 35 through the gears 36 and 37, thereby reciprocating the rod 34 and driving the agitator bar up and down through the throat 20 and the tuyère 11 (as indicated by the dotted and dash lines) to meet particular requirements.

60 As indicated in the drawing, the gear ratio between the pinion 36 and the ring gear 37 is four to one, which causes the agitator bar 30 to reciprocate four times within the retort 10 to every complete revolution of the feeding screw 23. 65 This ratio however may be changed according to varying conditions.

40 represents a passageway in the center of the agitator bar which may be employed to conduct air from the wind box 22 to the center of the retort as the agitator bar is reciprocated therein. This air passage also aids in cooling the agitator bar 30.

The agitator bar 30 working through the retort 10 during the firing period of the operating cycle, moves the coke forming therein in a rolling and

churning manner which prevents its coagulating into a unitary mass. It not only agitates the fuel by the intermingling of a moving object among the fuel particles but it does even more by the displacement which takes place. For example:—By the insertion of this agitator bar from an external point, the coal is moved which first fills in much of the space (openings, commonly called "voids") between the other particles of coal. Continuing the stroke, it rolls and churns the particles of coal being coked so that they do not adhere solidly one to another. The agitator bar should still continue its travel causing a gentle upheaving of the surface of the fuel bed, thereby keeping the fuel bed in a loose state, permitting a more uniform penetration of the forced or natural draft with less resistance, and thereby requiring a lower volume of air for combustion. Much the same action takes place on the return stroke of the agitator bar. The upper surface of the fuel bed gently smooths down, the coking particles below again churn about as they fill in the space formerly occupied by the agitator bar. In the meantime a small supply of new green coal has been fed in and the agitator bar is ready to start another cycle. Thus the fuel forms into small friable units composed of small coke particles approximating the size of the fuel being fed, but lightly adhering together. The spreading of this fuel by the agitator provides a homogeneous and very desirable type of fire bed. Thus the "coke tree" or "coining", hereinbefore mentioned, is eliminated as well as its consequent long firing periods and waste of fuel.

It will of course be understood that the screw while in operation may be continuously or intermittently rotated. Again the agitator member may be operated from or with the screw or other feeding device, or it may be independently operated either mechanically, or if desired manually.

Referring to Fig. 2, 41 represents a cylindrical cam member affixed to the shaft 28 and having a cam slot 42. 43 represents a rod head member secured at one end to the transmission rod 34 and passing at 44 through the housing which encases the cam member. The other end of the member 43 is provided with the follower 45 arranged to ride in and be guided by the cam slot 42 of the cam member 41. A hardened steel pin may be employed for this purpose. However it may be preferable to provide a stub shaft with a roller or other antifriction bearing arranged to ride in the cam slot 42.

Referring now to Figs. 3 and 4, 46 represents a vertically disposed agitating member arranged to reciprocate within the retort 10. The upper end of the member 46 may be provided with fingers or projections similar to that shown at 47 for further agitating the fuel. The agitating member may be made up of the upper and lower parts 48 and 49 which are rotatably secured to one another by means of the bolt 50 and spaced apart by a thrust bearing 51. The upper part 48 is provided with the spiral groove 52 formed longitudinally thereof and arranged to receive the inner end of the pin 53 secured in the casing 54, which in turn is secured to the base 18 of the retort. Thus as the agitating member 46 is reciprocated vertically, the upper part 48, is rotated by the action of the spiral groove with the pin 53.

The lower part 49 is not permitted to rotate by securing thereto the horizontal guide bars 55 and 56 which are also long enough to form a track to receive the full travel of the roller 57 on the end of the crank pin 58 extending laterally from the

lower end of the crank arm 59. The other end of the crank arm 59 is secured to the shaft 60 journaled in the frame 61.

62 represents a transmission shaft journaled in the upper part of the frame 61 and extending to the operating mechanism, from whence it derives its rotary motion. The shafts 60 and 62 are provided with the meshed gears 63 and 64 respectively. These gears may be changed to vary the ratio of the reciprocal movement of the agitator 46 with respect to the fuel feeding screw, but they are shown herein as one to one ratio gears.

The operation of this agitator is similar to that shown in Fig. 1 and produces the same effects.

15 In all these embodiments the agitators of this invention are arranged to reciprocate into the retort from or at the under side of the body of fire to churn the coking coals and displace them upwardly. If the coals have any tendency to coagulate, the force of the agitators is first directed on the particles of green coal and upwardly to and through the coking particles of the fuel, displacing considerable coal.

Our agitator may be arranged either to be wholly withdrawn from the combustion chamber when in its retracted position or may, when in such position, extend into the chamber to a greater or less degree.

During the dormant period of the operating cycle, coke particles of more solid texture may be formed but the agitation thereof during the firing period is sufficient to prevent the formation of large pieces or such a solid mass of coke as is found under normal operation with the present 35 automatic stokers.

We claim:

1. In an underfed stoker of the character described, the combination of a vertically disposed retort having an upwardly extending wall forming an enclosed throat in the upper portion of which combustion of the fuel occurs, a horizontal conduit communicating with the lower end of the throat at one side thereof, means for introducing fuel through the conduit into the bottom of the throat, the portion of the wall opposite the mouth of the conduit deflecting the fuel vertically upward through the throat, an agitator member having its free end extending into the throat through an opening in the bottom thereof, and means for moving said member substantially vertical into and out of the fuel in the throat below the zone of combustion to prevent the formation of solid masses of coke.

2. In an underfed stoker of the character described, the combination of a vertically disposed retort having an upwardly extending wall forming an enclosed throat in the upper portion of which combustion of the fuel occurs, a horizontal conduit communicating with the lower end of the throat at one side thereof, means for introducing fuel through the conduit into the bottom of the throat, the portion of the wall opposite the mouth of the conduit deflecting the fuel vertically upward through the throat, an agitator member having its free end extending into the throat through an opening in the lower portion thereof below the plane of the uppermost portion of said conduit, and means for moving said agitator member into and out of the fuel in the throat transversely to the path of the fuel entering the throat and below the zone of combustion to prevent the formation of solid masses of coke.

3. In an underfed stoker of the character described, the combination of a vertically disposed retort having an upwardly extending wall form-

ing an enclosed throat in the upper portion of which combustion of the fuel occurs, a horizontal conduit communicating with the lower end of the throat at one side thereof, means for introducing fuel through the conduit into the bottom of the throat, the portion of the wall opposite the mouth of the conduit deflecting the fuel vertically upward through the throat, an agitator member having its free end extending into the throat through an opening in said deflecting wall and having its longitudinal axis disposed transversely to the path of the fuel entering the throat, and means for moving said agitator member into and out of the fuel in the throat below the zone of combustion to prevent the formation of solid masses of coke.

4. In an underfed stoker of the character described, the combination of a vertically disposed retort having an upwardly extending wall forming an enclosed throat in the upper portion of which combustion of the fuel occurs, a horizontal conduit communicating with the lower end of the throat at one side thereof, means for introducing fuel through the conduit into the bottom of the throat, the portion of the wall opposite the mouth of the conduit deflecting the fuel vertically upward through the throat, a longitudinal arcuate agitator bar having its free end extending through an opening in the lower portion of the throat below the plane of the uppermost portion of said conduit, said bar being pivotally supported on an axis located at a point exterior to and above the bottom of the throat, and means for swinging said member on said axis into and out of the fuel in the throat below the zone of combustion to prevent the formation of solid masses of coke.

5. In an underfed stoker of the character described, the combination of a base arranged to be inserted in the bottom of a furnace, a vertically disposed retort supported by the base and having an upwardly extending wall forming an enclosed throat in the upper portion of which combustion of the fuel occurs, a horizontal conduit connected with the lower end of the throat at one side thereof, means for introducing fuel through the conduit into the bottom of the throat, the portion of the wall opposite the mouth of the conduit deflecting the fuel vertically upward through the throat, an arm pivotally secured to the base and arranged to swing in an arc, an agitator member attached at one end to the arm and having its free end extending through an opening in the lower portion of the throat below the plane of the uppermost portion of said conduit with its longitudinal axis disposed transversely to the path of the fuel entering the throat, and means for swinging said member to move its free end into and out of the fuel in the throat below the zone of combustion to prevent the formation of solid masses of coke.

6. In an underfed stoker of the character described, the combination of a base arranged to be inserted in the bottom of a furnace, a vertically disposed retort in said base having an upwardly extending wall forming an enclosed throat, tuyères forming the upper portion of the throat and having openings adjacent their upper ends for directing air into the throat to support combustion of the fuel, a horizontal conduit connected with lower end of the throat at one side thereof, means for introducing fuel through the conduit into the bottom of the throat, the portion of the wall opposite the mouth of the conduit deflecting the fuel vertically upward through the throat, an arm pivotally secured to the base and
